United States Patent Office

Des. 188,431
Patented July 19, 1960

188,431

TRAY

Jens H. Quistgaard, Copenhagen, Denmark, assignor to
Dansk Designs, Inc., Great Neck, N.Y., a corporation
of New York

Filed June 23, 1959, Ser. No. 56,500

Term of patent 14 years

(Cl. D44—10)

FIG. 1.

FIG. 2.

FIG. 3.

Fig. 1 is a top plan view of a tray showing my new design.

Fig. 2 is a side elevation thereof.

Fig. 3 is a smaller scale perspective view thereof.

The bowls shown in broken lines are for illustrative purposes only.

I claim:

The ornamental design for a tray, as shown and described.
